WEATHERPROOFING

Howard A. Smith, Chicago, Ill.

Application December 2, 1949, Serial No. 130,616

2 Claims. (Cl. 20—52.4)

1

This invention relates to a window construction, and more particularly to a weather-stripping assembly for a window construction.

The object of the invention is to provide a weather-stripping assembly for windows of the type having vertically-slidable sashes, the weather-stripping serving to provide a weather-tight joint between the sashes and the window frame, whereby the passage of air currents and the like between the sashes and window frame will be prevented.

Another object of the invention is to provide a weather-stripping assembly which will effectively stop the flow of air, dust, rain and the like around the slidable sashes of a window construction, the weather-strip assembly serving also to help maintain the sashes in alignment and insuring efficient operation thereof.

A further object of the invention is to provide a weather-strip assembly which is extremely simple and inexpensive to manufacture.

Other objects and advantages will be apparent during the course of the following description.

In the accompanying drawings forming a part of this application, and in which like numerals are used to designate like parts throughout the same:

Figure 1 is a horizontal sectional view taken through a window construction equipped with the weather-stripping assembly of the present invention;

Figure 2 is an enlarged horizontal sectional view showing the position of the parts when the sash is being moved into its position in the window frame;

Figure 3 is a horizontal sectional view showing the normal position of the rib in the sash groove;

Figure 4 is a vertical sectional view showing the arrangement of the spring members for urging the ribs into the grooves in the sashes and taken on the line 4—4 of Figure 1;

Figure 5 is a fragmentary perspective view showing a portion of the weather-strip assembly;

Figure 6 is a perspective view of the body member for attachment to the window frame;

Figure 7 is a perspective view of the support member for attachment of the other side piece of the window frame;

Figure 8 is a fragmentary perspective view showing one of the grooves in the sashes for receiving the movable rib;

Figure 9 is a perspective view showing a modified body member for use when a sash cord is being used.

2

Referring in detail to Figures 1 through 8 of the drawings, there is shown a window construction which includes a frame 20 that is adapted to be attached to the blind stop 21 in any suitable manner. The frame 20 includes a first vertically disposed side jamb 22 and a second vertically disposed side jamb 23 which is arranged in spaced parallel relation with respect to the side jamb 22, Figure 1.

10 Slidably arranged between the side jambs 22 and 23 are the usual pair of window sashes, the lower window sash being designated by the numeral 24, while the upper sash is designated by the numeral 25. The lower sash 24 is provided with a pair of longitudinally extending arcuate grooves 26 and 27, the grooves 26 and 27 extending longitudinally along the sides of the sash 24. The upper sash 25 is also provided with a pair of longitudinally extending grooves 26 and 27 for a purpose to be later described.

Arranged contiguous to the inner face of the side jamb 22 is a body member 28 which is preferably fabricated of a metal that is not affected by rain or the like. In other words, the body member 28 is shaped or provided with a pair of longitudinally extending, spaced parallel, arcuate portions 29 and 30. The arcuate portion 29 is seated in an arcuate recess 31 in the side jamb 22, while the other arcuate portion 30 is seated or received in a similar longitudinally extending arcuate recess 32 that is also arranged in the side jamb 22. The arcuate portions 29 and 30 serve to receive therein the usual sash balance rods 33, the sash balance rods 33 serving to maintain the sashes immobile in their adjusted positions.

35 The body member 28 is further provided with a first lip 34 that is adapted to be embedded in the blind stop 21, the body member 28 having a second lip 35 embedded between the filler strip 40 and the inside trim stop 19, whereby the body member 28 will be rigidly connected to the window frame, Figure 1.

The side jamb 22 is further provided with a pair of rectangular, longitudinally extending, spaced parallel cutouts 36 and 37. The body member 28 also includes a pair of spaced parallel, rectangularly-shaped, longitudinally extending sockets 38 and 39. The socket 38 is received or seated in the cutout 36 in the side jamb 22, while the other socket 39 is seated in the other cutout 37 in the side jamb 22.

45 Adjustably connected to the body member 28 is a pair of movable ribs 40. One of the ribs 40 is provided for each of the sockets 38 and

39, and the ribs 40 are mounted for movement into and out of engagement with the grooves 26 in the lower and upper sashes. The ribs 40 have a substantially U-shape and a plurality of spring members 41 serve to urge the ribs 40 into the 5 grooves 26 in the sashes, the spring members 41 being secured to the web portions of the sockets 38 and 39, as by welding.

For maintaining the ribs 40 operatively connected to the body member 28 there is provided a pair of flanges 42 which are integral with each of the ribs 40. The flanges 42 are adapted to abut or contact a pair of shoulders 44 on the body member 28, whereby the parts of the weather-stripping assembly will be maintained in operative or assembled relation at all times. This arrangement permits the ribs 40 to move in and out of the sockets 38 and 39, so that there will be provided a tight fit even after the grooves 26 have become enlarged through usage, shrinkage of the sash, or constant wear thereon.

The other side jamb 23 is provided with a pair of longitudinally extending, spaced parallel recesses 47 and 48 on its inner face. Arranged contiguous to the side jamb 23 of the frame 20 is a support member 49 which is also constructed of a non-corrosive material, and the support member 49 includes a pair of arcuate projecting portions 50 and 51 that seat in the recesses 48 and 47, respectively. Suitable lips 52 and 52' are arranged on opposite ends of the support member 49 and are adapted to be used for the same purpose as the previously-described lips 34 and 35. The arcuate projecting portions 50 and 51 of the support member 49 are for receiving therein the usual sash balance rods 33.

The support member 49 is further provided with a pair of spaced parallel, longitudinally-extending, projecting portions 53 and 54 which slidably seat in the grooves 27 in the other side of the upper and lower sashes of the window.

Referring now to Figure 9, there is shown a slightly modified body member 56. The body member of Figure 9 differs from the previously-described body member 28 in that the body member 56 is adapted to be used in those window constructions which use sash cords rather than sash balance rods. Thus, it will be seen that the body member 56 is provided with a pair of spaced parallel sockets 38 and 39 for receiving therein the spring members 41, but there are no arcuate portions 31 and 32 in the body member 56, since the sash cords can hang alongside the sockets 38 and 39, whereby the position of the sashes can be adjusted thereby.

From the foregoing it is apparent that a weather-stripping assembly has been provided wherein the air current, dust, rain and the like will be prevented from passing through or between the window sashes and the frame. The weather-stripping assembly includes arcuate portions for receiving therein the sash balance rods which are used in maintaining the sashes immobile in their adjusted positions. Further, the provision of the movable ribs 40 and the spring members 41 insures that the ribs 40 will be urged into the grooves 26 in the upper and lower sashes, so as to provide a tight joint between the sashes and window frame. The ribs will be maintained in operative relation, and the upper and lower sashes 24 and 25 will be urged against the projecting portions 53 and 54 of the support member 48, so that a tight joint will be provided all the way around the window sashes. However, the movable ribs 40 insure that normal sliding

movement of the sashes 24 and 25 will not be impaired. In the body member 56, shown in Figure 9, there are no arcuate portions for receiving sash balance rods, and the body member 56 is adapted to be used when the usual sash cords are used to manipulate the window sashes.

When using the weather-stripping assembly of the present invention, the sashes will be held in perfect alignment so that tipping of the sashes will be prevented and the sashes will operate quietly and easily. Further, the ribs will eliminate improper function of the sashes which might result from shrinkage of the parts.

What is claimed is:

1. In a window construction, a frame, an upper and a lower sash slidably arranged in said frame, there being a vertically-disposed groove arranged in each side of each of said sashes, a flat body member secured to said frame, a pair of spaced parallel U-shaped ribs movably connected to said body member and projecting into the grooves in one side of the sashes, a support member arranged on the other sides of said sashes and connected to said frame, a pair of arcuate projecting portions arranged in said support member and seated in the complementary grooves in said sashes, and resilient means for urging said ribs into the complementary grooves in the other sides of said sashes, outwardly extending flanges integral with each of said ribs, and a pair of inwardly extending shoulders on said body member adapted to overlie and engage the flanges on said ribs for limiting movement of said ribs away from said body member, and said body member and support members are each provided with a pair of spaced parallel elongated arcuate portions for receiving therein sash balance rods.

2. In a window construction, the combination with a window frame including a first vertically disposed side jamb and a second vertically disposed side jamb arranged in spaced parallel relation with respect to said first side jamb, an upper and lower sash slidably arranged between said side jambs, each of said sashes being provided with a longitudinally extending groove on opposite sides thereof, one of said side jambs being provided on its inner face with a pair of spaced parallel longitudinally extending recesses, there being a pair of longitudinally extending cutouts arranged in said first side jamb, a flat body member arranged contiguous to the inner face of said first side piece and secured thereto, said body member being provided with a pair of spaced parallel arcuate portions for receiving therein sash balance rods, said arcuate portions being seated in the recesses in said first side jamb, there being a pair of spaced parallel longitudinally extending sockets projecting from said body member and seated in the cutouts in the first side jamb, a pair of spaced parallel U-shaped ribs adjustably connected to said body member and mounted for movement into and out of the grooves in said sashes, outwardly extending flanges integral with each of said ribs and a pair of inwardly extending shoulders on said body member adapted to overlie and engage the flanges on said ribs for maintaining said ribs operatively connected to said body member, resilient means for urging said ribs into the grooves in said sashes, and said last means comprising a plurality of spring members secured to said body members and a support member connected to the inner face of said second side jamb, said support member being provided with a pair of spaced parallel projecting portions, said projecting por-

tions of the support member being seated in complementary grooves in said sashes.

HOWARD A. SMITH.
